Des. 238,886
Patented Feb. 17, 1976

238,886

PETRI DISH

Manuel Goy, 1215 S. Cloverdale Ave.,
Los Angeles, Calif. 90019

Filed Dec. 11, 1974, Ser. No. 531,667

Term of patent 14 years

Int. Cl. D24—02

U.S. Cl. D32—1 R

FIG. 1

FIG. 2

FIG. 4

FIG. 3

FIG. 5

FIG. 6

FIG. 7

FIG. 8

FIG. 9

FIG. 1 is a view in side elevation of a Petri dish, showing my new design;

FIG. 2 is a top plan view of the upper, cover portion thereof;

FIG. 3 is a view in side elevation of said upper cover portion;

FIG. 4 is a side elevation of said upper cover portion;

FIG. 5 is a bottom plan view of the lower portion of said Petri dish;

FIG. 6 is a view in central section of said bottom portion taken on line 6—6 of FIG. 5;

FIG. 7 is a side elevation of said lower portion;

FIG. 8 is a top perspective view of my Petri dish; and

FIG. 9 is a cross-sectional view taken on line 9—9 of FIG. 8.

I claim:

The ornamental design for a Petri dish, as shown.
